(57) **CLAIM**

I claim the ornamental design for a cup holder, as shown and described.

DESCRIPTION

FIG. 1 is a perspective view of a cup holder in accordance with our new design;

FIG. 2 is a side elevation view of the cup holder of FIG. 1, an opposite side elevation view being a mirror image thereof;

FIG. 3 is a top plan view of the cup holder of FIG. 1;
FIG. 4 is a rear elevation view of the cup holder of FIG. 1;
FIG. 5 is a bottom plan view of the cup holder of FIG. 1;
FIG. 6 is a front elevation view of the cup holder of FIG. 1;
and,

FIG. 7 is a perspective view of a cup holder in accordance with our new design; an exemplary cup is shown in broken lines.

The broken lines shown throughout the drawing figures are for illustrative purposes only and form no part of the claim.
